BY HIS ATTORNEY.

UNITED STATES PATENT OFFICE

125,268

DESIGN FOR A PIN ORNAMENT OR SIMILAR ARTICLE

Leo Glass, Monroe, N. Y.

Application December 26, 1940, Serial No. 97,612

Term of patent 3½ years

To all whom it may concern:

Be it known that I, Leo Glass, a citizen of the United States and resident of Monroe, in the county of Orange and State of New York, have invented a new, original, and ornamental Design for a Pin Ornament or Similar Article, of which the following is a specification, reference being had to the accompanying drawing, forming a part thereof, and of which Figure 1 is a view in front elevation of a pin ornament or similar article showing my new design; Fig. 2 is a view thereof in edge elevation; Fig. 3 is a view thereof in rear elevation; Fig. 4 is a sectional view thereof on the line 4—4 of Fig. 2; and Figs. 5, 6 and 7 are sectional views thereof on the lines 5—5, 6—6, and 1—7, respectively, of Fig. 1.

The characteristic feature of the design resides in the circular series of large outer translucent leaves surrounding the flower, in the design shown.

I claim:

The ornamental design for a pin ornament or similar article, substantially as shown and described.

LEO GLASS.
